CLAIM

The ornamental design for a weighted jump rope exercise device, as shown and described.

DESCRIPTION

FIG. 1 is a top front perspective view of a weighted jump rope exercise device, showing our new design in a condition of use;

FIG. 2 is a bottom front perspective view in a condition of use thereof;

FIG. 3 is a top front perspective view;

FIG. 4 is a bottom, rear perspective view of FIG. 3 thereof;

FIG. 5 is a left side elevation view of FIG. 3 thereof;

FIG. 6 is a right side elevation view of FIG. 3 thereof;

FIG. 7 is a top plan view of FIG. 3 thereof;

FIG. 8 is a bottom plan view of FIG. 3 thereof;

FIG. 9 is a front side elevation view of FIG. 3 thereof; and,

FIG. 10 is a rear side elevation view of FIG. 3 thereof.

The broken lines in the drawings depict portions of the weighted jump rope exercise device that form no part of the claimed design. The broken lines shown in FIGS. 1 and 2 are for the purposes of illustrating environmental structure, which form no part of the claimed design.
